Laurens Jaques

UNITED STATES PATENT OFFICE.

THORVALD HEYERDAHL, OF CHRISTIANIA, NORWAY.

CONNECTION BETWEEN A WATER-TUBE AND A PRESSURE-BASIN MOUNTING THE WATER-TUBE.

1,342,286.

Specification of Letters Patent.

Patented June 1, 1920.

Application filed August 9, 1919. Serial No. 316,425.

To all whom it may concern:
Be it known that I, THORVALD HEYERDAHL, a subject of the King of Norway, residing at Christiania, Norway, have invented 5 certain new and useful Improvements in a Connection Between a Water-Tube and a Pressure-Basin Mounting the Water-Tube; and I do hereby declare the following to be a full, clear, and exact description of the 10 invention, such as will enable others skilled in the art to which it appertains to make and use the same, reference being had to the accompanying drawings, and to letters or figures of reference marked thereon, which 15 form a part of this specification.

The problem of connecting steel tubes to water basins under high pressure affords the difficulty that water is liable to leak out between the concrete and the steel tube. 20 This is a very serious drawback, particularly for the reason that it is practically out of the question to repair an embedded tube of this kind and in any case repairs require a long time to be carried out. 25 In order to obtain a tight connection and at the same time facilitate the conditions for repair, the tube according to the present invention is not embedded in the concrete but is mounted by means of a radial flange fastened to the tube in an opening of considerably larger diameter than the exterior diameter of the tube.

The said flange on the tube may rest directly on the concrete or it may be mounted 35 on an inwardly projecting flange embedded in the concrete around the opening in the same.

On the drawing is illustrated two embodiments of this invention.

40 Figure 1 is a diagrammatic section of a connection according to the invention. Fig. 2 is a detail section on a larger scale through part of the flange. Fig. 3 is a diagrammatic section through a modified form 45 of the invention.

Fig. 4 shows the present invention in practice.

1 indicates the pressure basin which terminates in a concrete block 2. Said concrete block is provided with openings 3, the diameter of which is bigger than the exterior diameter of tube 4 which is mounted coaxially in the opening by means of flange 6 fastened on the tube near its end.

55 Said flange as indicated in Fig. 1 may

have the shape of a dome, the exterior edge surface of which rests on the bottom of an annular groove 8 in the concrete block 2.

As indicated in Fig. 2 the edge 7 may be provided with a tightening device comprising 60 a downwardly projecting annular rib 9 and a channel 10 of wedgeshaped cross section inside said annular rib 9, said channel 10 being provided with a rubber packing or the like.

As indicated in Fig. 3 the flange 6 instead of resting directly on the concrete may be connected with an inwardly projecting flange 5 embedded in the concrete around the opening 3.

As it will be noted both the embodiments of the invention here specified afford the possibility of dismounting the connection without breaking up the concrete.

In Fig. 4 my invention is illustrated as it 75 is used in practice. This figure shows a lake having a rock bed and shows a pressure tunnel cut in the rock and leading to the base thereof where the device of the present invention is located. At this point the steel 80 tube opens into the pressure tunnel and extends from this point to the power station located below. The concrete block in the pressure tunnel and the supporting flange for the tube which is embedded in the concrete are diagrammatically shown in this figure.

Claims.

1. In a connection between a water tube and a pressure basin mounting the water tube 90 by means of a radial flange on the same in an opening in the wall of the pressure basin said opening having a considerably larger diameter than the exterior diameter of the tube.

2. In a connection between a water tube and a pressure basin mounting the water tube by means of a radial flange on the same in an opening in the wall of the pressure basin, the edge of said radial flange being 100 supported by an inwardly projecting flange embedded in the concrete around the opening.

In testimony that I claim the foregoing as my invention I have signed my name in 105 presence of two subscribing witnesses.

THORVALD HEYERDAHL.
